UNITED STATES PATENT OFFICE.

RUSSELL HARRIMAN, OF KANSAS CITY, MISSOURI.

PIPE-CLEANING DEVICE.

1,219,734.

Specification of Letters Patent. Patented Mar. 20, 1917.

Application filed March 19, 1915. Serial No. 15,460.

To all whom it may concern:

Be it known that I, RUSSELL HARRIMAN, a citizen of the United States, residing at Kansas City, in the county of Jackson and 5 State of Missouri, have invented certain new and useful Improvements in Pipe-Cleaning Devices, of which the following is a specification.

This invention relates to improvements in 10 pipe cleaners, and the object is to provide a cheap and simple device for cleaning out the bowls, stems and mouth-pieces of ordinary pocket smoking-pipes, and especially those having stems and mouth-pieces of curved or 15 irregular outline or extending at more or less sharp angles to the pipe bowl. With this end in view the invention aims to provide means comprising a quill feather which has been so prepared as to adapt it to 20 form easily and effectively this cleaning function in connection with pipes of the character described. It is also sought to obtain a device which will be inexpensive to produce by employing material for which 25 little use of value has heretofore been found for other purposes.

With the above general object in view the invention will now be described with reference to the accompanying drawing illustrating 30 a mode of carrying the same into practice, after which the particular features believed to be novel will be pointed out and claimed. In the drawing—

Figure 1 is a plan view of a quill feather 35 embodying the invention;

Fig. 2 is a detail view on a larger scale showing the quill portion of the feather, and Fig. 3 is a section on the line III—III of Fig. 2;

Fig. 4 is a detail view of a modified form 40 and Fig. 5 is a section on the line V—V of Fig. 4;

Fig. 6 is a fragmentary sectional view 45 illustrating the use of the device in cleaning out the mouth-piece of a pipe;

Fig. 7 is a sectional view illustrating the manner of introducing the quill end of the feather through the bowl of the pipe into the stem portion; and

Fig. 8 is a similar view showing the manner 50 of using the device for cleaning out the stem of the pipe bowl.

Referring to the drawing, the invention aims to use a grade of quill feather 2 of intermediate size, as illustrated in Fig. 1 showing 55 the actual size of same, of which partici-

ular grade of feather no special use is made to any extent outside of grinding them up for the purpose of filling a cheap class of pillows. The tip of this feather is clipped 60 away as at 4 for exposing a comparatively stiff portion of the quill 6 so as to adapt the same to be readily inserted into the mouth-piece 8 of the pipe (see Fig. 6). In the stiff or quill end of the feather is made a gash or 65 notch 10, preferably facing at right angles to the plane of the vanes 12, and between this gash or notch and the end of the quill the latter is cut away along approximately the axial line of the quill (as shown at 14) 70 and to practically a point to form a scoop or spoon portion of this part of the quill. This scoop portion may be on the same side of the quill as the notch 10 as illustrated in Figs. 1 and 2, or on the opposite side as 75 shown in Fig. 4.

In the use of the device, the scoop or spoon portion 14 is employed to scoop out the bowl 16 of the pipe, the sides of this scoop portion providing strong scraping 80 edges which act effectively to loosen up the deposits on the walls of the pipe and clean the same. For cleaning the stem 18 of the pipe bowl the point of the quill is presented at the opening of the stem bore and then 85 further pushing of the device causes it to bend at the notch 10 (see Fig. 7) and also causes the scraping edges of the scoop portion 14 to be spread still farther apart; thereafter the manipulation of the device 90 by partial rotation of the remaining portion of the feather imparts an effective scraping movement to the scoop portion. The device may then be withdrawn so as to insert the scoop portion bent in the opposite direction 95 for cleaning the opposite side of the bore of the stem 18.

The mouth-piece 8 is cleaned as already indicated by presenting to the opening of the mouth-piece the clipped end 4 of the 100 device and pushing the same through in the manner illustrated in Fig. 6, the inclination of the barbs or vanes 12 in the direction in which they are moved tending to enhance the cleaning action because of the effective 105 manner in which they wipe against the interior of the bore of the mouth-piece. After the feather has been used in the above-described manner it may be readily employed in the way illustrated in Fig. 8 to swab 110 out the bore of the stem 18 by holding the larger end of the quill and pressing the

smaller and more flexible portion of the feather against the mouth of said bore, thereby causing the same to bend and break and pass into the bore in doubled-up form 5 as shown. Both the stem 10 and the bowl of the pipe may thus be thoroughly cleaned out by using the device in this doubled form, the cleaning of the bowl being best accomplished by movement of the larger end 10 of the feather in crank-like fashion around the mouth of the bowl.

It will thus be apparent that an effective and convenient device is provided for cleaning both the stem and mouth-piece as well 15 as the bowl of the pipe. The device can of course be made in various sizes for use with various styles of pipes, and is obviously adapted for cleaning pipes having either the ordinary straight stem or the inclined stem 20 and curved mouth-piece such as herein shown. It is found that cleaners made of these quill feathers are of just the right stiffness for accomplishing the desired purpose of cleaning and scraping without scratching 25 or in any way injuring the interior portions of the pipe, thus having a marked advantage over some of the forms of cleaners now in use having a wire core which tends to mar

the pipe and form pits that collect impurities and render it almost impossible to keep 30 the pipe perfectly clean. Furthermore, by following the outline of steps as given above, all the parts of the pipe can be cleaned without soiling the hands with any of the used portions of the feather barbs or vanes. Pref- 35 erably the feathers used in the manufacture of these cleaners will all be properly sterilized in the course of their manufacture.

Claims:

1. A pipe cleaner comprising a quill 40 feather having its quill end cut approximately half in two adjacent the vanes of the feather to render the quill flexible at said cut portion, said quill end of the feather being cut away on one side to form a scoop 45 portion between said first cut and the end of said quill portion.

2. A pipe cleaner comprising a quill feather having a notch in its quill end adjacent the vanes of the feather to render the 50 quill flexible at said notched portion, said quill end of the feather being cut away along approximately the axial line of the quill to form a scoop portion between said notch and the end of said quill portion.

RUSSELL HARRIMAN.
